UNITED STATES PATENT OFFICE

ERNST WASA BRÄUER, OF BERLIN-GRUNEWALD, GERMANY

FEEDING OF VAPOR TURBINES

Application filed August 29, 1930, Serial No. 473,717, and in Germany September 6, 1929.

The present invention relates to the feeding of vapor turbines, that is to say of prime movers of the turbine type, the working fluid of which consists of minute liquid globules intimately mixed with vapor of the same liquid.

This mixture is obtained by expanding in a nozzle a liquid, for example, water, raised to a high temperature and pressure.

Such vapor turbines are distinguished, for example, from steam turbines, by the fact that they have no steam generator but only a heater completely filled with liquid, which is maintained at a pressure great enough to prevent evaporation at the temperature to which the water is heated.

Feeding of this liquid heater is naturally more difficult than the feeding of a steam generator inasmuch as in relation to a unit weight of liquid, less heat is converted into work than in steam turbines.

In addition, vapor turbines in general work with higher pressures than are usual at the present time with steam turbines.

For the reasons given, it will be seen that the question of feeding is much more important and difficult in connection with vapor turbines than with steam turbines.

The usual method of feeding by means of a piston pump cannot be utilized, since vapor turbines run at much higher revolutions per minute than steam turbines (apart from the de Laval turbine) and consequently a greater ratio of reduction in the transmission is required in order to drive a piston pump.

According to the present invention, the feeding device for the liquid heater of the vapor turbine is operated by steam or the like in a series of pulsations and comprises a chamber shut-off from atmosphere, and completely enclosing the movable parts of the feeding device, the exhaust from the chamber after giving up its heat to the feed for the liquid heater, being condensed in a heat-transferrer.

In accordance with the present invention, it will be seen that no moving part of the pump passes through the wall of the enclosing chamber to the atmosphere so as to re-

quire packing; the tightness of the chamber being maintained solely by the packing of stationary parts and in consequence no loss of heat from the system occurs if leakage takes place from one side to the other of a moving part of the pump.

In vapor turbine installations, the thermo-mechanical conditions are such that a substantial quantity of steam is produced, only when the pressure has been reduced to a small fraction of the original pressure, and consequently the heated pressure water itself cannot be applied to the driving of the pulsating feeding device, since its volume is only slightly different from the volume of the liquid to be fed.

Referring to the accompanying drawings, which show two illustrative forms of the invention by way of example:—

Figure 1 shows a diagrammatic view of a vapor turbine installation with feeding devices according to one form of the present invention;

Figures 2 and 3 are longitudinal sections through one form of feeding device, and

Figure 4 a corresponding cross-section;

Figure 5 shows partly in section an electrically-operated valve gear for the feeding device,

Figure 6 shows a longitudinal section through a modified form of the invention.

Figure 7 is a diagrammatic showing of an installation embodying the form shown in Figure 6.

In carrying the invention into effect according to one form as shown in Figure 1 and applied to a vapor turbine in which the working fluid consists of an intimate mixture of steam and minute globules of water, the turbine, 1, is provided with nozzles, 2, in which the "fog" or vapor is produced.

According to the form of the invention under description, the heater consists of a tubular coil, 4, a heat-insulating jacket, 5, and a liquid-fuel burner, 6.

Admission of fuel is effected automatically by a regulating valve, 30, which by means of a pipe, 17, is subjected to the pressure in the main pipe, 3, containing the pressure water, the arrangement being such that

when a predetermined pressure is exceeded, the fuel is throttled or shut off.

A hand-operated shut-off valve is indicated at 31.

5 The same burner supplies heat to a steam generator which consists, according to the present example, of vertical water tubes, 7, connected to annular water and steam headers, 8 and 9, the steam generated passing 10 through a pipe, 10, to a feed cylinder, 11, provided with two tubular extensions, 12 and 13.

The feed-water passes from the condenser, 14, of the turbine by way of a non-return 15 valve, 15, to the feed cylinder, this transfer being effected automatically. If the piston, 33, (Figure 2) moves downwards in the cylinder the non-return valve, 15, closes and the feed-water passes by way of a second non-return valve, 16, to the inner coil, 18, of a heat-transferrer surrounding the jacket of the heater, 4.

20 The outer coil, 19, of the heat-transferrer receives by way of a pipe, 24, the exhaust steam from the feed cylinder, 11, this exhaust steam being condensed on the walls of the inner coil, 18. The condensate is returned through a pipe, 21, by way of a valve device arranged in the tubular projection, 30 12, an intermediate container, 22, and a second valve device in the extension, 12, and thence passes by way of a pipe, 23, to the steam generator, 7.

25 A throttle valve, 26, is inserted in the steam pipe, 10, leading from the steam header, 9, to the feed cylinder, 11, the steam header, 9, being connected in addition by way of a safety valve, 32, to the outer coil, 19, of the heat-transferrer.

30 Further, a pipe, 25, connects the lower extension, 13, of the feed cylinder with the inner coil, 18, of the heat-transferrer, this inner coil, 18, being also connected by means of a pipe, 20, to the heater, 4.

35 In the feed cylinder, 11, a piston, 33, is provided, the piston rod, 39, of which is formed at its lower end as a piston, 34. The upper part of the piston rod, 39, is provided with a lateral projection or feather, 42, disposed in a groove, 43, in a drag valve, 40, sliding in the tubular extension, 12, this valve, 40, being held in its end positions by means of a spring, 38, co-operating with a lever, 36, engaging in a recess, 37. It will 40 be understood that owing to the ends of the projection, 42, coming in contact with the corresponding ends of the groove, 43, the piston rod, 39, when near its extreme upper or lower positions carries the valve, 40, with it.

45 In the position shown in Figure 2, it is assumed that the piston, 33, is moving upwards owing to the pressure of water from the heater, 4, acting through coil 18 and pipe 25 on the small piston, 34.

The action of the feeding device described is as follows:—

In the heater, 4, a pressure of 150 atmospheres exists and in the steam boiler, 7, 8, 9, 70 a pressure of 155 atmospheres.

Assuming that the piston, 33, is in its highest position, the connections due to the valve, 40, are such that the space above the piston, 33, is connected with the steam generator by way of the pipe, 10, this connection being preferably controlled by a partial closing of the valve, 26. At the same time the path from the intermediate container, 22, to the steam generator, 7, 8, 9, 80 through the pipe, 23, is open so that the contents of this container pass into the generator. That is, the container 23 is in free communication with the steam generator, and the steam will first flow into the container, and then, as soon as the pressure is equalized, the liquid will flow down by gravity into the steam generator. The downward movement of the piston forces the water below it by way of the non-return valve, 16, into the inner coil, 18, of the heat-transferrer and thence into the heater itself.

85 As the piston approaches its lowest position, the valve, 40, changes over. The path to the steam space of the generator, 7, by way of the pipe, 10, is then closed and also the connection between the intermediate container, 22, and the steam generator by way of the pipe, 23, while the connection, 21, between the intermediate container, 22, and the lower end of the coil, 19, of the heat trans- 90 ferrer, is opened, so that condensate passes from the coil, 19, into the container, 22.

95 When the connections are thus changed over, naturally at first steam that has collected as explained above in the intermediate container, 22, flows into the outer coil, 19, of the heat-transferrer.

100 The total heat of the steam so far as it has not been converted directly into mechanical work by the movement of the piston and so far as it has not been dissipated by conduction, is thus transferred to the feed-water for the heater, since the steam condenses on the outer surface of the inner coil, 18, of the heat-transferrer.

105 An upward movement of the piston, 33, follows under the pressure below the auxiliary piston, 34, the condensate from the vapor turbine, 1, passing automatically into the space below the piston.

110 The pressure of the feed can be adjusted by altering the duration of the stroke of the piston by means of the throttle valve, 26, or by means of an adjustable throttle device in any suitable position.

115 This effect can also be obtained by means of an electrically-controlled valve gear, of which one form is shown in Figure 5.

120 Instead of the drag valve, 40, in the upper extension, 12, a valve, 50, is provided 125

which is connected by links and a double lever, 51, to an iron core, 52. This core is movable in a branch from the casing, 53, of non-ferrous metal, for example brass, and is controlled by a coil, 54, acting against a spring, 55. Excitation of the coil is effected by means of a contact maker driven by a clockwork, the speed of which is adjustable by means of a lever, 57.

10 With such an external control for the valve gear, the means for causing the piston, 33, to move upwards can be omitted and the piston becomes merely a free-moving partition separating steam and water.

15 In the forms of the invention described, all the elements of the valve gear lie inside the extension, 12, so that it is necessary to provide fluid-tight joints only for the pipe connections, the points where leakage may 20 occur lying inside a closed space.

25 On account of the very great sensitivity to additions of feed of the liquid heater as here applied, in contrast to a steam boiler, this condition is of considerable importance.

Figures 6 and 7 show a modified form of the invention in which the feeding device, working with a succession of pulsations, is driven not by steam from a boiler arranged 30 as an accessory to the water heater, but by steam from expanded pressure water taken from the heater or the main pipe 3.

In this form of the invention, therefore, the steam boiler, 7, 8, 9, is omitted and the 35 burner, 6, in consequence heats only the coils, 4, of the water heater.

This simplified form of the invention consists of a cylinder, 71, in which works a piston, 70, connected with a substantially 40 larger piston, 73, in a cylinder, 72. The cylinder, 71, is connected by way of a non-return valve, 75, with the pipe, 74, which in turn is connected to the condenser, 14, the non-return valve, 75, thus corresponding to 45 the non-return valve, 15, in Figure 1. The cylinder, 71, is also connected by way of a non-return valve, 76, which corresponds to the non-return valve, 16, in Fig. 1, to the inner coil, 18, of the heat-transferrer. The 50 large piston, 73, is provided with an extension rod, 94, which ends in a perforated piston, 78, working within a hollow drag valve, 79.

The piston, 78, in the end positions of the 55 piston, 73, does not come into contact directly with the bottom of the hollow valve, 79, and with a perforated plate, 80, screwed into the other end, but springs, 81, 82, are interposed which butt against movable perforated 60 discs, 83 and 84.

The hollow valve, 79, is prevented from turning by a longitudinal groove (not shown in the drawings) into which enters a guide pin secured to the valve housing, 85.

65 In addition recesses, 86, are provided

into which in the end positions of the valve, a spring detent, 87, enters.

The hollow valve, 79, in its end positions alternately connects with the pipe, 88, leading to the outer coil, 19, of the heat-transferrer and with the branch, 89, of the valve casing, which is connected by way of a pressure-reducing valve, 90, of any suitable construction to a pipe, 91. This pipe is branched off from the main pipe 3.

70 A non-return valve, 92, is provided in the piston, 73, which in the form shown in the drawings is subject to the action of a comparatively weak spring, 93, to ensure its return to the lowest position if its own weight 75 is insufficient.

The action of this form of the invention is as follows:—

Heated pressure water of high pressure, 80 for example 120 atmospheres, passes through the pipe, 91, to the branch, 89, by way of the pressure-reducing valve, 90, where its pressure is considerably reduced, for example to 12 atmospheres, as soon as the piston, 73, moving downwards from the position shown causes the valve, 79, by means of the spring, 81, and disc, 83, to assume its lowest position in which the interior of the hollow valve, 79, is connected with the branch, 89, and shut off from the pipe, 88. 85 In this position the detent, 87, under the action of its spring snaps into the upper recess, 86, and holds the valve in this position until by upward movement of the piston, 73, the valve under the action of the spring, 82, and the disc, 84, is again forced into the position shown.

90 In the lowest position of the valve, the steam generated from the pressure water 105 expanded from 120 to 12 atmospheres, flows below the large piston, 73, which together with the small piston, 70, moves upwards against the action of the weak spring, 93. In this way the water in the small cylinder, 110 71, sucked out of the condenser, 14, is forced by way of the non-return valve, 76, through the pipe, 77, into the lower end of the inner heat-transferrer coil, 18.

At the end of the upward stroke of the 115 piston, the valve, 79, is changed over and the small cylinder, 71, is again filled by way of the non-return valve, 75, with water from the condenser while the condensing steam from the large cylinder, 72, passes through 120 the pipe, 88, into the outer coil, 19, of the heat-transferrer.

The lower end of this outer coil is connected by a pipe 100 with a container, 122, which on its side is preferably connected by 125 way of a float valve 101 and a pipe 102 to the pipe, 74, coming from the condenser, 14. The condensate flows from the outer coil, 19, into the container 122. When the latter is 130 filled to a certain height the float valve 101

opens and is closed again as soon as the container is nearly emptied.

In this manner all the heat is utilized as in the forms of the invention previously described, the water heater being fed by means of the slow-working feeding device.

The non-return valve, 92, in the piston, 73, serves to prevent too great an increase of pressure in the cylinder, 72, in consequence, for example, of leakage past the piston, 70. Any partly evaporated and condensed fluid which has passed into the interior of the cylinder, 72, can then escape through the opened non-return valve, 92, and on the next 15 downward stroke of the piston, 73, will be withdrawn through the pipe, 88, together with the condensate from the steam under the piston, 73.

In order to protect the turbine, 1, from the effects of a pulsating feed, a balancing storage vessel 60 is provided on the high-temperature side, that is, between the turbine, 1, and the heater, 4.

This arrangement of storage vessel has the special advantage in connection with vapor turbines that the installation is not exposed to danger from the completely closed liquid heater, the pressure in which, due for example to an obstruction in one of 30 the pipes, might rise to a dangerous degree.

In addition, the storage vessel in the case of vapor turbines has all the advantages of a heat buffer which are provided by the boiler in the case of steam reciprocating and 35 turbine engines.

Quite apart, however, from the balancing of pressure oscillations, the use of the storage vessel in connection with the method of feeding according to the present invention, 40 is important for averaging the temperatures of successive volumes of liquid.

In consequence of the slow pulsations of the feed, without the balancer, undesirable energy oscillations would occur in the turbine not only due to pressure changes but 45 far more to temperature changes.

By the introduction of the balancer, it is possible for the first time to utilize in practice all the potential advantages of the 50 vapor turbine.

What I claim is:—

1. In a turbine system including a source of heated water under pressure, a turbine driven by a mixture of water and steam developed from said heated water under pressure, a condenser connected to said turbine, a heat transfferer including a heating coil, a second coil surrounding said heating coil, a feeding device comprising a working cylinder, means connecting said cylinder to said condenser, a non-return valve in said connecting means, a second means connecting said heating coil to said cylinder, a non-return valve in said second connecting means, 60 a second cylinder of larger diameter than

said first cylinder and located in substantial alignment therewith, a piston rod extending within both said cylinders, pistons on said rod one in each of said cylinders, a piston on said rod outside said cylinders, a slideable hollow drag valve, means controlled by said third piston to connect one side of the piston in the larger cylinder alternatively through said hollow valve with a steam inlet and a steam outlet, means connecting said steam inlet to said source of heated water under pressure, a pressure reducing valve in said last connecting means, and means connecting said steam outlet to said second coil.

2. In a system as claimed in claim 1, said means controlled by the third piston including discs on either side of the piston slideable in the hollow valve to engage the ends thereof, a spring between each of the discs and the piston, and spring controlled means releasable under a predetermined pressure for normally holding said hollow valve at either end of its movement, said hollow valve having ports therein connected with the steam inlet and the steam outlet respectively at one end and the other of the movement of the valve.

3. In a system as claimed in claim 1, said means controlled by the third piston including discs on either side of the piston slideable in the hollow valve to engage the ends thereof, a spring between each of the discs and the piston, and spring controlled means releasable under a predetermined pressure for normally holding said hollow valve at either end of its movement, said hollow valve having ports therein connected with the steam inlet and the steam outlet respectively at one end and the other of the movement of the valve, said hollow valve having depressions therein, said spring controlled means including a detent, and spring means pressing said detent into engagement with said depressions.

4. In a system as claimed in claim 1, a pressure releasing valve in the piston in the larger cylinder.

5. In a turbine system including a source of heated water under pressure, a turbine driven by a mixture of water and steam developed from said heated water under pressure, a condenser connected to said turbine, a heat transfferer including a heating coil, a second coil surrounding said heating coil, a feeding device comprising piston means, means connecting one side of said piston means to said condenser, a non-return valve in said connecting means to permit flow of fluid from said condenser to said piston means only, means connecting the same side of the piston to said heating coil, a non-return valve in said second connecting means to permit flow of fluid from said piston means to said heating coil only, means connecting the other side of said piston means

to a source of heated fluid under pressure, means connecting said second side of the piston means to said second coil, and a slide valve operated by said piston rod to open one of said last named connecting means and to close the other and vice versa.

5 6. In a system as claimed in claim 5, means constantly urging said piston means in the direction of said second side.

10 10. In testimony whereof, I have affixed my signature.

ERNST WASA BRÄUER.
